AUTOMATIZED ACCOUNTING MEDIUM

George L. Whitehead, Huntingdon, Pa.

Application October 24, 1942, Serial No. 463,217

6 Claims. (Cl. 283—66)

This invention relates to an improved type of sheet or leaf for record books used in general accounting, and the many special phases thereof.

The present invention affords a new and novel technique in regard to the posting of individual items chronologically over predetermined periods of time, and the handling of column summaries at the conclusion of one period and the beginning of the next consecutive period, without necessitating the duplication of figures on any one period sheet or the carrying forward of summaries, by transfer, from one period sheet to the sheet for the next period.

The object of the present invention is to provide an unique form of accounting and statistical medium, for practicing the aforesaid technique, by means of which data may be accumulated, distributed, segregated, and/or analyzed, automatically and concurrently, as and when the details are being recorded.

While the present invention is applicable to all, or substantially all, branches of accounting, and for the recording of statistics, the form of the invention hereinafter described, as a specific embodiment thereof, is directed to what is generally known as the "auxiliary ledger," the purpose of which, in an accounting ensemble, is to provide separate repositories or compartments for detailed accounts with customers and/or creditors.

In the accompanying drawings:

Fig. 1 is a face view of a sheet or book leaf constructed in accordance with the principles of the present invention;

Fig. 2 is a perspective view of one form of book make-up consisting of a plurality of sheets, similar to the one shown in Fig. 1, with complete alternate lateral marginal areas of successive sheets removed in accordance with the present invention; and

Fig. 3 is a perspective view of another form of book make-up consisting of a plurality of series of sheets similar to the one shown in Fig. 1, but showing different sub-divisions of the marginal areas, and complete marginal areas of successive sheets removed in accordance with the invention.

As shown in Fig. 1, the full sheet 1 is bounded by outer marginal edges 2, 3, 4 and 5, connecting the points 6, 7, 8 and 9 of the right angle corners of the sheet.

The sheet 1 includes a binding area 10, defined by a line 11 paralleling the top edge 2 of the sheet 1 and connecting a point 12, on the

marginal edge 3, with a point 13, on the marginal edge 5 of the sheet 1.

The binding area 10 is provided with a plurality of openings 14 for the reception of binding posts, rings or convolutions 15 of a suitable loose leaf book, such as illustrated in Fig. 2, which includes, preferably, a pair of rectangular covers 16, 16, hinged to any suitable back structure 17, to which the securing elements 15 of the loose leaf binder are attached to complete the book.

The sheet 1, in the particular adaptation of the invention illustrated in the present instance, also includes a central main record area 20, bounded by the line 11 at the top of said area, from the point 21 to the point 22 thereon, which are respectively spaced inwardly from the marginal edges 3 and 5 of the sheet 1. The lower boundary of the main recording area 20 is defined by the lower edge of the sheet 1, between the points 23 and 24 spaced inwardly from the lower corners 8 and 9, respectively of the sheet 1.

The lateral marginal edges of the main recording area 20 are defined by lines 25 and 26, extending parallel to and spaced inwardly from the marginal side edges 3 and 5, respectively, of the sheet 1, said lines extending from the points 21 and 22, respectively, along the line 11 to points 23 and 24, respectively, along the bottom edge 4 of the sheet 1.

At the opposite sides respectively of the main recording area 20, the sheet 1 is provided with lateral complementary marginal areas 30 and 40 respectively. The area 30 is bounded at its top by the line 11, from the point 21 thereon to the point 12 at the intersection of the line 11 and edge 3 of the sheet 1. Along one side, the area 30 is bounded by the marginal edge 3 of the sheet, from the point 12 to the corner 8. Along its bottom, the area 30 is bounded by the bottom edge 4 of the sheet, from the corner 8 thereof to the point 23 where the right boundary line 25 of the main area 20 intersects with the bottom edge 4 of the sheet. Along its left side the area 30 is bounded by the line 25, from the point 23 on the bottom edge 4 of the sheet to the point 21 on the line 11 aforesaid.

The complementary area 40 is similarly bounded by the line 11, from the point 13 to the point 22; by the line 26 from the point 22 to the point 24; by the edge 4, from the point 24 to the corner 9; and by the edge 5, from the corner 9 to the point 13 aforesaid.

The top portion 20a of the main recording area 20, and the top portions 30a and 40a, respectively, of the complementary areas 30 and

40, from the line 11 to a line 11a, which extends parallel to the line 11 from a point 31 on the right marginal edge 3 of the sheet to a point 41 on the left marginal edge 5 of the sheet, and which crosses the vertical division lines 25 and 26 at the points 32 and 42, are devoted to general information, such as identification of the book for which the sheet is intended, the month, year, day of month, and other pertinent information and instructions, column headings or titles, etc.

The intermediate portions 20b, 30b and 40b of the areas 20, 30 and 40, respectively, which extend from the cross line 11a to a cross line 11b, are devoted to daily entries of the individual customer's or creditor's accounts and the summaries for the period covered by the particular sheet, respectively, in the present instance, said line 11b extends parallel to and is spaced from the bottom edge 4 of the sheet, from a point 33 on the right marginal edge 3 to a point 43 on the left marginal edge 5 of the sheet 1.

The lower portions 20c, 30c and 40c of the areas 20, 30 and 40, respectively, are devoted to the sheet summaries for the period covered by the particular sheet, the consecutive number of the sheet as it will appear in its place in the book, i. e., the page number etc., these portions extending from the line 11b to the bottom marginal edge 4 of the sheet 1.

In the present instance the portion of the cross line 11a of the right complementary area 30, from the point 31 to the point 32, and that corresponding portion of the cross line 11a of the left complementary area 40, from the point 41 to the point 42, and the longitudinal lines 25 and 26, which divide the central area 20 from the complementary areas 30 and 40, from the points 32 and 42 on the line 11a to the points 23 and 24 respectively on the bottom edge 4 of the sheet, are perforated completely through the sheet 1 and form separating lines by which the intermediate and bottom portions 30b—30c, 40b—40c, of the complementary areas 30 and 40 may be selectively removed from the sheet 1, leaving the top portions 30a or 40a of these areas, as the case may be, permanently attached to the top portion 20a of the main central area 20 of the sheet.

The removable areas 30b—30c, 40b—40c are subdivided by vertical lines of perforations 34, 35, and 44, 45, which extend parallel to and intermediate the lines 25 and 26 and the respectively adjacent side edges 3 and 5 of the sheet 1, from points 36 and 46 on the cross line 11a, to points 37, 47 on the bottom edge 4 of the sheet, whereby the removable portions 30b—30c, and 40b—40c of the side areas 30 and 40 respectively are divided into relatively separable parts 30d, 40d, 30e, 40e, and 30f, 40f respectively.

In using the sheet depicted in Fig. 1, in a book such as that shown in Fig. 2, alternate pages 1a of the book have the removable sections 40b—40c of the left complementary areas 40 detached from the sheets 1 of which these pages are formed, while the intermediate pages 1b of the book have the removable sections 30b—30c of the right complementary areas 30 detached from the respective sheets 1 of which these particular leaves of the book are formed.

The daily entries of the individual customers or creditors are listed in progression in the blocks of the horizontal rows thereof, under the columns headed "Day of the month," from left to right.

At the end of the working period as covered 75

by one of the leaves 1, for example the alternate sheets designated as 1a, 1a in Fig. 2, the customer's or creditor's summaries, for that working period, are posted in the intermediate portion 30b of the right complementary area 30 which has been retained, and the removable section 40b—40c of the left complementary area 40 of that page sheet are detached therefrom.

On the intermediate pages 1b, 1b the daily entries are also made consecutively, from left to right, in the horizontal rows of blocks under the name spaces of each particular customer, etc., but the summaries for the period represented by each particular sheet 1b are posted in the portions 40b of the lateral areas 40, and the removable portions 30b—30c of the right complementary area 30 are detached.

By this particular technique, it is unnecessary to carry forward from one sheet to the next any figures whatsoever, nor is it necessary to duplicate any figures on any sheet, the summaries on the sheet for the period preceding the current working period at all times being visible at one side of the current sheet, thus errors which commonly arise in transferring figures from one sheet to another are completely eliminated.

The bottom portions 30c and 40c of the leaves 1a and 1b carry the general accumulative summaries for the whole period as gained by adding the individual items posted in the vertical columns at the bottoms of which the accumulated amounts appear as footings.

The foregoing description affords a general understanding of the basic principles upon which the present invention is predicated, with Figs. 1 and 2 serving as illustrations thereof. Fig. 3 is directed to a more specific application of the invention for keeping records of transactions with individual customers or creditors.

As shown in Fig. 1, each of the supplementary areas 30 and 40 is divided into four vertical columns with the columns in area 40 being headed "Gen. Led." (general ledger), "Cr. Bal." (creditor balance), "Dr." (debit) and "Cr." (credit) respectively and in the order named, beginning at the marginal edge 5 and ending at the division line 26, and with the columns in the area 30 being headed "Dr.," "Cr.," "Cr. Bal.," and "Gen. Led.," respectively, in the order named from the division line 25 to the marginal edge 3 of the sheet 1.

The main area 20 is divided into horizontal sections which are each divided into a plurality of subdivisions which permit distributional accounts being "set up" in these sections respectively as "Purchases," "Accounts payable," "Cash," and "Cash discount," etc., on horizontal lines, instead of downwardly in the usual vertical columns, with the top horizontal space in each horizontal section reserved for the creditors' names and addresses, etc.

Any desired amount of space may be provided, at 50, between the line labeled "Purchases" and the line labeled "Accounts payable" for itemizing the purchases or grouping the purchases made by various departments, etc.

Also, below the line labeled "Cash discount," in each instance, greater space may be provided at 51 for similar reasons.

As previously noted, in the sheet or leaf for one minimum working period (7 days, as shown, for example, in Fig. 1) the transactions for each consecutive day are posted in the area 20 in horizontal progression, from left to right across the

sheet. At the end of the minimum working period covered by the sheet, the summaries of the transactions for that period are posted in either the complementary area 30 or 40, the credits being posted in the "Cr." column, the debits in the "Dr." column, and the balance in the "Cr. Bal." column. The other of the complementary areas 30 or 40 as the case may be is detached from the sheet.

Assuming that the summaries are posted in the area 30 in one sheet, the area 40 would be detached. On the next consecutive upper sheet the area 30 would be detached, exposing the summaries on the area 30 of the previous sheet. At the end of the minimum period covered by the topmost sheet, the summaries of the transactions for that period are listed in the area 40 and the balances showing in the area 30 of the next lower sheet are taken into consideration in calculating the balances at the end of the period covered by the then topmost sheet, before starting a new sheet for another consecutive minimum period. The new balance is then posted in the column headed "Cr. Bal." to be visible during the posting of the individual items on the next consecutive sheet and during the calculating of the balance at the end of the next period covered by the next consecutive sheet.

The general or accumulative summaries for each entry sheet are calculated and posted in the bottom section 30c or 40c as the case may be, in the spaces opposite the respective lines labeled "Purchases," "Accounts payable," "Cash," "Cash discount," "Unpaid balances of all accounts on this sheet at beginning of period" and "Trial balance."

It will be noted that, in the above listings of postings no mention has been made of any postings in the outside columns labeled "Gen. Led." These columns are used only at the end of an intermediate period, such as at the end of a month; or at the end of a maximum period for the book, such as the end of the year; or at the end of a group of pages devoted to creditor's accounts whose names begin with the same letter of the alphabet, with one group for "A," one for "B," and so on throughout the whole alphabet.

Each letter of the alphabet may be broken down into subdivisions, if desired, such as "Aa" to "Ae," "Af" to "Al," etc., with the outside area 30f or 40f of the complementary area 30 or 40 of the appropriate sheets left in place and carrying the data for the particular alphabetical range of the group, for the intermediate monthly period, or for the maximum yearly period, as the case may be.

At the end of the maximum period covered by any single book, such as a year, the topmost sheet on which the general accumulative summaries for the whole year appear, is used as the first sheet of a new book for the next period. This may be the original last sheet of the old book or a carbon copy thereof which at the beginning of a new year will clearly indicate the condition of the account of each customer or creditor and the condition of the accounts as a whole as a basis for beginning the accounts of the individuals for the next period.

Fig. 3 illustrates the sheet (original or carbon) completed at the closing of one maximum period employed at the bottom or beginning of the book for the next consecutive period, this base sheet being designated as 1—A, it being the top sheet of the group devoted to creditors whose names begin with the letter A.

In making up the book (Fig. 3) a plurality or group of sheets is devoted to the letter Z, this group being superimposed on the sheet 1—A, and a subsequently superimposed group devoted to the letter A. In actual practice there would be one such group for each letter of the alphabet and in the present illustration (Fig. 3) those relating to the letters B to Y inclusive have been eliminated to avoid unnecessary duplication in the illustration.

10 The first, third and fifth sheets z¹ have the outside portions 40f of the supplemental areas 40 removed while retaining the portions 40d and 40e thereof. The entire supplemental areas 30 of these sheets z¹ are removed.

15 The second, fourth and sixth sheets have the outside subdivisions 30f removed while retaining the areas 30d and 30e. The entire supplemental areas 40 of this group of "Z" sheets is removed.

20 The seventh sheet z³ of the Z group retains the outside subdivision 40f of the complementary area 40, to provide for the general ledger figures for all of the sheets, for all of the creditors in the Z group, for the intermediate (monthly) period, while the entire complementary area 30 of this seventh sheet is removed.

25 The above arrangement is carried out for each letter of the alphabet, each month, with either the outside subdivision 40f retained, as in the case of the "Z" group, or with the outside subdivision 30f retained, as illustrated in the case of the "A" group.

30 Assuming the maximum period covered by book to be one year, and the intermediate period covered by each group of sheets to be one month, and each minimum period covered by each sheet to be one week (7 days), there would be twelve groups for each letter in the alphabet, and four or five sheets in each group, one for each week (4 week, 28 day month) and an extra one for the part week (29, 30 or 31 day month).

35 The top sheet of the "A" group would carry the yearly totals, balances, etc., for the entire maximum period, to be used as the basis for starting a book for the next maximum period, as the sheet 1—A in Fig. 3.

40 Obviously, the reverse order could be used, i. e., the alphabet could be used with A at the bottom and Z at the top, in which case the topmost sheet of the topmost Z group would function as the final summary sheet for the maximum period to form the basis for the book of the next maximum period.

45 55 A book may be made up of any desired number of full page sheets 1 prior to the beginning of use thereof, or the pages may be inserted one after another at the beginning of each working period. In any event, the entries must be made first on what normally would constitute the last page of the book, and are devoted to the earliest period covered by the book. The entries for subsequent periods are made on the next upper leaves consecutively.

60 65 Whether the book is made up completely at the start, or made up periodically by adding a page-sheet at the beginning of each working period, the removal of the section of the sheet which is to serve as the current page at the beginning of a working period is preferably not effected until

70 75 the start of the period, thus the accountant is always assured of having available the proper complementary area 30 or 40, as the case may be, for the summaries of the current period, and is also assured that the complementary area show-

ing the summaries for the preceding working period are always exposed to view at one side of the leaf for the current period.

Use of the leaf-sheets of the present invention, as described above, results in an ability to keep the details of recorded data covered, while exposing their extended summaries, at will. This is made possible by changing the direction of chronological insertion of entries from the common vertical progression, i. e., down a column, from top to bottom of a page, or sheet to a horizontal progression from one lateral extremity of the recording area of a page or sheet to the opposite lateral extremity thereof; (left to right) with the summaries extended to the sides of the sheets in a reciprocative horizontal progression, i. e., from right to left on one page and from left to right on the next page, and so on throughout the book, whereby the accumulation of data on each page is always visible for carrying-on, on the next page, without necessitating any transfer or duplication of figures on any page or from one page to another.

By use of the present invention, another change in the chronological succession of entry is effected, i. e., the data is always recorded and accumulated with the items of the earliest period covered by a volume on the lowest or normally last page thereof, and the items of the latest current period on the topmost leaf of the volume, insuring that the most recent information being compiled for management shall always be presented first to the eye of the person inspecting the record.

The use of the present invention affords still further advantages and saving of time over the conventional methods of accounting and recording of data. Accounts, or other compartmental equivalents may function continuously and concurrently from sheet to sheet along horizontal channels, by which the focal points for assembling related data need no longer be completely isolated one from another, and a number of these may function together on the same sheet, with greater accounting efficiency than could be accomplished when each is isolated from the others, thus making real effective control possible over "Receivables," "Payables," and/or other details, by providing for complete and unassailable verification up to the point where each consecutive sheet is found to reconcile up to that point, making it impossible for obscure errors to delay verification until such errors are found and corrected, as is the case where verification must be deferred until the end of a working period.

The foregoing makes possible the ability to have at one's finger tips the completely verified "open balances" of all accounts or equivalents currently existing at any time, in a static exhibit such as is now available only by taking off existing balances and transferring them to a schedule, which, having been deferred until a closing period may not reconcile with its control after it has been summarized.

The method afforded by the present invention makes it feasible and scientific to make initial routine entries pertaining to purchases and sales direct to a customer's or creditor's ledger or equivalent instead of first recording such items in a so called medium of original entry, in which such items are distributionally segregated and from which they must be posted into the media from which the final results are to be extracted.

Adoption of the present invention brings into being a medium in which automatic distribution of the components of an entry is provided for as received, and in which chronological succession

of entry is preserved, with the result that the auxiliary ledger functions as a self-contained vehicle requiring no help to take over automatically distributed data directly from invoices and arrange it in the exact niches in which it must be placed when it becomes a part of any final result, however that result is arrived at. This results in saving of time, eliminates lost motion, unnecessary effort and delay represented by duplications of all kinds, from the ubiquitous subtotal to the posting required to carry forward data from one medium to another.

While but one application of the principles of the present invention has been set forth herein, it is obvious that these principles may be applied to other forms and systems of keeping records of various kinds, with the full page-sheets modified as to data areas, location of removable sections, distribution of the lines of perforations affording removal of various sections of the sheet, etc., without departing from the spirit of the invention, as set forth in the appended claims.

I claim:

1. A recording sheet adapted to be bound with others of its kind in superposed succession with the marginal side top and bottom edges of the sheets substantially flush, said sheet comprising an appropriately designated main vertical central area, and an appropriately designated complementary vertical area at each of the opposite sides of said central area, predetermined sections of each of said complementary areas being selectively detachable from the remainder of the sheet by tearing along vertical lines of perforations extending parallel to the marginal side edges of said sheet and defining the lateral extents of said detachable sections respectively.

2. A recording sheet adapted to be bound with others of its kind in superposed succession with the marginal side top and bottom edges of said sheets substantially flush, said sheet comprising an appropriately designated main vertical central area, and an appropriately designated complementary vertical area at each of the opposite sides of said central area, predetermined sections of each of said complementary areas being selectively detachable from the remainder of the sheet by tearing along vertical lines of perforations extending parallel to the marginal side edges of said sheet and along transverse lines of perforations disposed parallel to and spaced downwardly from the top marginal edge of said sheet and extending inwardly from said marginal edges across said complementary areas, said vertical and transverse lines of perforations defining the lateral and vertical extents of said detachable sections respectively.

3. A recording sheet adapted to be bound with others of its kind in superposed succession, with the lateral and transverse edges of said sheets substantially flush, said sheet comprising an appropriately designated main vertical central area and an appropriately designated complementary vertical area at each of the opposite sides of said central area, and with major portions of each of said complementary areas upwardly from the bottom marginal edge of said sheet being detachable from the remainder of the sheet by tearing along vertical lines of perforations paralleling the lateral marginal edges of the sheet, and by tearing along transverse lines of perforations disposed parallel to and spaced downwardly from the top marginal edge of said sheet and extending inwardly from said lateral edges of said sheet to the lateral edges of said main central area.

leaving upper portions of said complementary areas intact and integral with said central area.

4. A recording sheet adapted to be bound with others of its kind in superposed succession, with the lateral and transverse edges of said sheets substantially flush, said sheet comprising an appropriately designated main vertical central area, and an appropriately designated complementary vertical area at each of the opposite sides of said central area, and with major portions of said complementary areas upwardly from the bottom marginal edge of said sheet being detachable as a whole or selectively as vertical sub-portions thereof from the remainder of the sheet by tearing along vertical lines of perforations paralleling the lateral marginal edges of the sheet, and by tearing along transverse lines of perforations disposed parallel to and spaced downwardly from the top marginal edge of said sheet and extending inwardly from said lateral edges of said sheet to the lateral edges of said main central area, leaving upper portions of said complementary areas intact and integral with said central area.

5. A recording sheet adapted to be bound with others of its kind in superposed succession, with the lateral and transverse edges of said sheets substantially flush, said sheet comprising an appropriately designated transversely extending binding area adjacent and paralleling the top marginal edge of the sheet from side to side thereof, an appropriately designated main vertical central area below said binding area, and an appropriately designated complementary vertical area at each of the opposite sides of said central area below said binding area, with major portions of said complementary areas upwardly from the bottom marginal edge of said sheet being detachable as a whole or selectively as vertical sub-portions thereof from the remainder of the sheet by

tearing along vertical lines of perforations paralleling the lateral marginal edges of the sheet, and by tearing along transverse lines of perforations disposed parallel to and spaced downwardly from the top marginal edge of said sheet and extending inwardly from said lateral edges of said sheet to the lateral edges of said main central area, leaving upper portions of said complementary areas intact and integral with said central area.

6. A recording sheet adapted to be bound with others of its kind in superposed succession, with the lateral and transverse edges of said sheets substantially flush, said sheet comprising an appropriately designated main vertical central area provided with horizontal rows of data receiving spaces, and an appropriately designated complementary vertical area at each of the opposite sides of said central area provided with horizontal rows of data receiving spaces as lateral extensions of said main area rows respectively, with major portions of said complementary areas upwardly from the bottom marginal edge of said sheet being detachable as a whole or selectively as vertical sub-portions thereof from the remainder of the sheet by tearing along vertical lines of perforations paralleling the lateral marginal edges of the sheet, and by tearing along transverse lines of perforations disposed parallel to and spaced downwardly from the top marginal edge of said sheet and extending inwardly from said lateral edges of said sheet to the lateral edges of said main central area, leaving upper portions of said complementary areas intact and integral with said central area whereby predetermined portions of the horizontal rows of data spaces in said complementary areas may be removed selectively.

GEORGE L. WHITEHEAD.
